Primary Examiner — Garth Rademaker*Assistant Examiner* — Llorellys Martinez-Rivera(74) *Attorney, Agent, or Firm* — Silicon Valley Patent Group LLP(57) **CLAIM**

The ornamental design for a narrow beam LED module optic, as shown.

DESCRIPTION

FIG. 1 is a top perspective view of a narrow beam LED module optic showing our new design;

FIG. 2 is a top perspective, exploded view of a narrow beam LED module optic showing our new design;

FIG. 3 is a top plan view thereof;

FIG. 4 is a bottom plan view thereof;

FIG. 5 is a front view thereof;

FIG. 6 is a back view thereof;

FIG. 7 is a left view thereof; and,

FIG. 8 is a right view thereof.
